UNITED STATES PATENT OFFICE

KENNETH L. SMITH, OF DES PLAINES, ILLINOIS

WALL STRUCTURE

Application filed August 10, 1929. Serial No. 384,969.

The main objects of this invention are:

First, to provide an improved wall structure which is highly efficient from the standpoint of insulation against heat, cold and moisture.

Second, to provide a wall structure formed of blocks which may be laid without mortar or cement joints, and at the same time is very strong.

10 Third, to provide a wall structure formed of blocks which when erected constitutes a substantially integral unit.

Fourth, to provide an improved reinforce or tie means for walls formed of blocks.

15 Fifth, to provide a wall structure embodying these advantages which may be quickly and easily erected and one which is economical.

Objects relating to details and economies of 20 my invention will appear from the description to follow. The invention is defined and pointed out in the claims.

A structure which is a preferred embodiment of my invention is illustrated in the 25 accompanying drawings, in which:

Fig. 1 is a fragmentary perspective view of a building embodying the features of my invention.

Fig. 2 is a fragmentary horizontal section 30 on a line corresponding to line 2—2 of Fig. 1.

Fig. 3 is a fragmentary horizontal section on a line corresponding to line 3—3 of Fig. 1.

Figs. 4, 4A and 4B are perspective views 35 of the three types of blocks employed by me.

Fig. 5 is a fragmentary perspective view of one of the insulating panels.

Fig. 6 is a fragmentary perspective view of one of the air pocket closure members.

Fig. 7 is a fragmentary view mainly in vertical section on a line corresponding to line 40 7—7 of Fig. 8 showing an adaptation of my improvements to wooden floor joists.

Fig. 8 is a fragmentary horizontal view partially in section on line 8—8 of Fig. 7.

45 In the structure illustrated in the accom-

panying drawings, 1 represents the foundation wall or footing and 2 a basement floor. The side walls are formed of three styles of blocks 3, 4 and 5. All of these blocks are rabbeted along their upper longitudinal edges to provide external longitudinal shoulders 6 and have corresponding internal longitudinal shoulders 7 along their bottom longitudinal edges, these shoulders forming interlocking parts when the blocks are superimposed in a wall, as is clearly shown in Fig. 1.

The blocks 3 have vertical holes 8 therein.

The blocks 4 have vertical holes 9 therein opening on the inner sides of the blocks. 60 These blocks are provided with reinforces 10 and 11 indicated by dotted lines.

The blocks 5 have two rows of vertical holes 12 arranged in staggered or overlapping relation, and also a row of holes 13 preferably of triangular cross section, alternate holes 13 being arranged in an intermediate relation relative to the pairs of rows 12.

The blocks 5 have longitudinal channels 14 on their upper faces disposed between the series of holes 12 providing inwardly facing shoulders 15, these shoulders having outward offsets 16 therin between the holes 12, and longitudinal raised portions 17 providing outwardly facing shoulders 18 adapted to engage with the shoulders 15.

The blocks 3 and 4 have longitudinal recesses 19 at the top and bottom.

The blocks 3 and 5 have external shoulders 20 at one end and internal shoulders 21 at 80 the other, the shoulders of adjacent blocks being adapted to interlock and being inclined as illustrated to facilitate assembling. The blocks 4 have corresponding shoulders at their outer sides only.

In the wall structure illustrated, the basement walls are formed of the blocks 3. The main side walls of the building are formed of the blocks 5 while a row of the blocks 4 are inserted in the walls to receive the edges of 90

the floors 22. As the blocks 3 are laid, anchoring rods 23 project from the foundation or footing into certain of the vertical holes of the blocks 8 and are anchored therein by means of the filling 24. Vertical anchoring rods 25 are arranged through aligned holes in the blocks 3, 4 and 5 and embedded in this filling. The edges of the floor extend into the openings 9 in the blocks 3, the reinforcing bars 26 being engaged with the upright reinforcing bars 25. I also preferably provide horizontal tie rods 27 which are laid in the channels formed by the recesses 19 in the top and bottom of the blocks 3 and 4.

15 With this arrangement, the floors are in effect built into the wall and are very securely anchored and supported, the floors with their reinforcing members constituting tie members for the walls with the result that the structure is very rigid and the floors are capable of sustaining very heavy loads.

20 To increase insulation of the walls, I provide insulating panels 28 which are inserted into aligned holes 12, these holes or pockets having vertical grooves 29 at the ends thereof adapted to receive the edges of the insulating partitions 28, supporting them in a central position.

25 To prevent concrete falling into these pockets while the floor is being laid, I provide cover plates 30 having offset portions 31 fitting into the pockets and opening to the spaces 19 in the blocks 6.

30 The corner blocks 55 are modified by providing the same with vertical cylindrical openings 56, these blocks also having vertical shoulders 57 at one side adapted to coact with the shoulders on the ends of the abutting blocks. The corner blocks are arranged in 35 alternating relation providing, however, a vertical cylindrical pocket through the wall adapted to receive the reinforcing bar 58 which is embedded in a filling 59 providing a substantial corner tie or anchoring means for the corner blocks. The horizontal tie bars 25 are passed around these vertical tie bars 58, further anchoring or tying the walls at the corners.

35 In the modification shown in Figs. 7 and 8, special blocks 32 are provided at the floor line, these blocks being substantially the same as the blocks 3 with the exception that their inner walls are shortened to provide spaces 33 to receive the ends of the wood joist 34. 40 In this embodiment, the wall section illustrated is made up of blocks 5, the blocks 32 being superimposed thereon at the floor line, a row of blocks 3 upon the blocks 32, and the blocks 5 above, this being a special adaptation of my improvements, facilitating the use of joist as distinguished from a monolithic floor.

45 Walls embodying my improvements may be quickly and economically erected, are very effectively insulated against heat, cold and

moisture and are very strong and rigid even when laid without mortar. In the embodiment illustrated in Fig. 1, the floors are not only effectively supported and connected to the walls but they in turn constitute bracing 70 and tie members for the walls of the building.

I have not attempted to illustrate or describe various modifications and adaptations other than those illustrated which I contemplate as it is believed that this disclosure will 75 enable those skilled in the art to embody or adapt my improvements as may be desired.

Having thus described my invention, what I claim as new and desire to secure by Letters Patent, is:

1. A wall structure comprising a plurality of blocks having external shoulders along their top longitudinal edges and corresponding internal shoulders along their bottom longitudinal edges, each of said blocks having a plurality of vertical openings therethrough disposed longitudinally and in staggered relation, the end walls of said openings being vertically grooved, said blocks also having longitudinal grooves in the tops thereof disposed between said vertical openings and corresponding longitudinal ribs on the bottoms thereof, said grooves and ribs having lateral enlargements constituting co-engaging key members, the ends of said blocks having vertical co-engaging shoulders, and partition strips of insulating material disposed in aligned vertical openings in said blocks with their vertical edges engaged in said grooves in the ends of the blocks. 100

2. A wall structure comprising a plurality of blocks having external shoulders along their top longitudinal edges and corresponding internal shoulders along their bottom edges, each of said blocks having a plurality of vertical openings therethrough disposed longitudinally and in staggered relation, said blocks also having longitudinal grooves in the tops thereof disposed between said vertical openings and corresponding longitudinal ribs on the bottoms thereof, said grooves and ribs having lateral enlargements constituting co-engaging key members, the ends of said blocks having co-engaging shoulders, and partition strips of insulating material disposed in aligned vertical openings in said blocks. 105

3. A wall structure comprising a plurality of blocks having external shoulders along their top longitudinal edges and corresponding internal shoulders along their bottom longitudinal edges, each of said blocks having a plurality of vertical openings therethrough disposed longitudinally and in staggered relation, said blocks also having longitudinal grooves in the tops thereof disposed between said vertical openings and corresponding longitudinal ribs on the bottoms thereof, said grooves and ribs having lateral enlargements constituting co-engaging key members, the ends of said blocks having co-engaging shoulders, and partition strips of insulating material disposed in aligned vertical openings in said blocks. 110

115

members, the ends of said blocks having vertical co-engaging shoulders.

4. A wall structure comprising a plurality of blocks having aligned vertical holes therein running normal to the horizontal course joints, the ends of said holes being vertically grooved, and continuous partition strips disposed in said aligned holes with their edges in supporting engagement with said grooves.

10 In witness whereof I have hereunto set my hand.

KENNETH L. SMITH.
